FREQUENCY CONTROL APPARATUS
AND METHOD

Arthur E. Harrison, Rockville Centre, N. Y., assignor to The Sperry Corporation, a corporation of Delaware

Application July 30, 1943, Serial No. 496,716

26 Claims. (Cl. 315—6)

1

This invention relates to microwave apparatus and methods and is especially concerned with apparatus and methods for accurately obtaining ultra high frequencies especially for measurement, standardization and like purposes.

Microwave apparatus has developed to the extent where there is need for accurate frequency measurement, and for setting up reliable primary and secondary frequency standards. In some known crystal-controlled frequency multiplier microwave devices of the cavity resonator type, a limited number of different frequencies may be accurately obtained by resonator tuning adjustment, but to obtain further frequencies it is necessary to change crystals or make other extensive adjustments or both. The present invention is intended to provide a source of a much larger number of obtainable ultra high frequencies than are available in such known sources.

It is a major object of this invention to provide novel ultra high frequency methods and apparatus for selectively obtaining and reproducing any of a large number of distinct frequencies accurately.

A further object of the invention is to provide novel methods and apparatus for accurately obtaining a sequence of desired discrete ultra high frequencies from a cavity resonator device.

A further object of the invention is to provide novel methods and apparatus for energization of microwave devices of the cavity resonator type.

A further object of the invention is to provide novel cavity resonator apparatus wherein electron concentration or grouping in the electron beam is phase modulated, so that the apparatus may be tuned to selectively produce any of a large number of rationally related frequencies, such as sideband or harmonic frequencies or both, which can be separately extracted for desired utilization.

Further objects of the invention will presently appear as the description proceeds in connection with the appended claims and the annexed drawings wherein:

Fig. 1 is a combination schematic and diagrammatic view useful for illustrating a part of the principles of the invention;

Fig. 2 is a diagrammatic view illustrating the relation of the carrier and some sideband frequencies obtainable from the apparatus of Fig. 1;

Fig. 3 is a diagrammatic view illustrating carrier and sideband output relations obtainable from the apparatus of Fig. 1;

Fig. 4 is a further schematic and diagrammatic view illustrating the invention as applied

to a frequency multiplier device of the cavity resonator type; and

Fig. 5 is a diagrammatic view illustrating sideband and harmonic frequency relations obtainable from the apparatus of Fig. 4.

Fig. 1 illustrates a part of the principles applicable to the invention employs a conventional two-resonator amplifier of the velocity modulation type wherein a beam of electrons is projected from a cathode 11 through hollow conductive input and output resonators 12 and 13. The cathode is heated by a suitably energized filament 14, and enclosed by a glass wall 15 sealed in vacuum tight relation to resonator 12. Resonators 12 and 13 are interconnected by a rigid drift passage tube 16. Input grids 17 and 18 are provided in the path of the beam in a wall of resonator 12 and the adjacent end of tube 16. Output grids 19 and 21 are provided in the path of the beam in a wall of resonator 13 and the adjacent end of tube 16. A suitably shaped collector electrode 22 seals off resonator 13 about grid 19.

One end wall portion 23 of resonator 13 is annularly crimped so as to be flexible, whereby relative separation of grids 21 and 19 and variation of the natural frequency of resonator 13 may be accomplished by adjustment of screws 24 reacting against a support 25 fixed with tube 16, screws 24 being threaded in a mount 26 fixed to the body of resonator 13. Thus resonator 13 may be tuned to different natural frequencies by alteration of physical characteristics such as its volume and internal shape by adjustment of screws 24. The unidirectional accelerating voltage for cathode 11 is derived from battery 27 having its negative terminal connected to cathode 11 and its positive terminal connected to grid 17 through ground and resonator 12. A suitable alternating voltage source of modulation frequency 28 is connected to the cathode through a condenser 29 which blocks off unidirectional current from battery 27.

Resonator 12 is excited by high frequency energy transmitted from a suitable source 31 by coaxial line 32. The output of resonator 13 is extracted by coaxial line 33.

Sources 28 and 31 may comprise any suitable, preferably stabilized, sources of alternating voltage having accurately controllable frequencies. The modulation frequency from source 28 is substantially lower than the exciting frequency from source 31.

In operation, while the electron beam from cathode 11 is passing between grids 17 and 18 of

resonator 12, the electrons in the beam are alternately accelerated and retarded, or velocity modulated, by interaction with the resonator field between the grids. The field within resonator 12 is excited and maintained by energy from source 31 at the predetermined frequency of the source 31, to be hereinafter called the carrier frequency. Resonator 12 is resonant to this frequency.

As a result of this velocity modulation, electrons in the beam travelling at different velocities form spaced concentrations in electron density in the beam during passage along tube 16, this action being also known as velocity grouping along the beam.

The electron concentrations in density, or electron bunches or groups as they are sometimes called, in the beam arrive at output grids 21 and 19 with a repetition rate equal to the frequency of resonator 12, and represent an electron current of that frequency having a phase relation with respect to the input resonator wave which is a function of and determined by the transit time between the resonators 12 and 13.

The spacing of the electron groups or bunches along the beam is determined by the carrier frequency of the field within resonator 12 and the initial electron velocity. In usual cavity resonator amplifier operation, the beam acceleration voltage is constant, so that the length of tube 16 can be selected to obtain optimum interaction between the electron beam and the field within resonator 13.

This velocity grouped electron beams, in passing between output grids 21 and 19, excites oscillations within resonator 13, and the alternating field within resonator 13 extracts energy from the beam. This extracted energy sustains oscillations within resonator 13 and is available for output on line 33. The frequency of this extracted energy is determined by the above described rate of repetition of the electron bunching in the beam, which in usual amplifiers of this type is the input or carrier frequency. As in usual amplifier operation, screw 24 is adjusted until the natural frequency of resonator 13 corresponds to this carrier frequency for optimum output.

In general, the above described operation is the same as described in Varian Patent No. 2,242,275, to which reference is made for further detail.

In addition to the available output carrier frequency, there is available in the grouped beam a desired sequence of other discrete frequencies which may be obtained by suitably tuning resonator 13. These other frequencies, which are not available in the usual amplifier output, are made available in the beam by the modulation action of source 28.

The modulation voltage from source 28 causes variation of the beam acceleration voltage at the modulation frequency, and thereby correspondingly varies the initial velocities and the transit times of the electrons in the beam. This modulation therefore correspondingly varies the phase of the resulting electron concentrations relative to the input resonator field, and thus produces what will be called phase modulation of the electron grouping in the beam. In this manner, the electron beam grouping is phase modulated at a relatively low frequency which, for an amplifier device, need not bear any other particular relation to the velocity modulation or carrier frequency.

It is also observable that the electron density of the concentrations or groups is varied with the

accelerating voltage, thus providing some amplitude modulation.

The bunched electron beam, in other words, is phase modulated proportionately to the alternating modulating voltage impressed on cathode 11. It is not essential that the modulation voltage be impressed on the cathode. Such voltage may be impressed on any other beam control electrode for varying electron flight time, such as on an added grid in the beam path between cathode 11 and grid 17, or on a cylindrical or other suitably shaped electrode insulatingly mounted in tube 16. These proposed modifications are equally applicable to the apparatus shown in Fig. 4 and discussed hereinafter.

The above described modulation effects produce an available output from the phase modulated grouped beam which consists of the carrier frequency and an infinite sequence of sum and difference sideband frequencies spaced at intervals equal to the modulation frequency. Suitable tuning of resonator 13 makes the carrier or any of those side band frequencies within the tuning range of resonator 13 selectively available on line 33. Screws 24 are simply adjusted until the natural frequency of resonator 13 corresponds to the desired sideband frequency. By maintaining the modulation frequency high as compared to the band width permitted by the Q of resonators 12 and 13, there will be substantially no output on line 33 except the carrier or the particular sideband for which resonator 13 is tuned. The tuning mechanism can be suitably calibrated for selecting sidebands corresponding to a particular modulation frequency.

Fig. 2 shows diagrammatically the spacial relation between the carrier frequency F and typical sideband frequencies indicated in dotted lines, available in the output of the apparatus of Fig. 1.

Fig. 3 illustrates typical curves showing graphically the relation between the amplitudes of the carrier and sideband frequencies obtainable by the apparatus of Fig. 1 as a function of the modulation voltage. These curves were made from tests using a cavity resonator type amplifier similar to Fig. 1. Curve A represents the carrier or normal operating frequency of the amplifier, while curves B, C and D represent respectively first, second and third sideband frequencies having in this instance 50 megacycle per second separation. The sideband maxima are clearly distinct and tunably separate, and their approximately equal amplitude is indicated. The output milliamperes were measured through a crystal connected at line 33, while the modulation voltage was that superposed on the cathode acceleration voltage.

Fig. 4 illustrates the invention as embodied in a cavity resonator type multiplier device 34 which comprises input and output resonators 35 and 36. A drift tube 37 extends between the resonators, being coupled to resonator 35 by a relatively high capacity section 40 for reducing the necessary size of resonator 35. A cathode 38, heated by a filament 39 energized from a suitable source 41, is arranged to project a beam of electrons through the resonators 35 and 36.

Resonator 36 is formed with a flexible end wall 42 connected to tube 37, and tuning adjustment screws 43 are provided to react between a mount 44 rigid with tube 37 and a lug 45 rigid with the body of resonator 36. Resonator 35 is also provided with a flexible end wall 46 secured to tube 37, and tuning adjustment means (not shown) may be provided for resonator 35. Also, if de-

sired, gang tuning mechanism similar to that disclosed in Letters Patent No. 2,311,658 may be employed for proportionately tuning resonators 35 and 36. Input grids 47 and 48 are provided for resonator 35, and output grids 49 and 51 are provided for resonator 36 in the electron beam path.

As illustrated, resonator 36 is smaller than resonator 35, and so may be tuned to higher resonant frequencies. Device 34 is a frequency multiplier wherein resonator 36 is capable of tuning adjustment until its natural frequency is a harmonic of a resonant frequency of resonator 35.

A source of voltage having a constant frequency is provided as indicated at 52. This source may be a conventional crystal-controlled oscillator capable of extremely accurately maintaining a fixed relatively low frequency output, this fixed frequency in a preferred embodiment of the invention being 3.75 megacycles (mc.) per second. This fixed frequency output is delivered by a coaxial line 53 to a frequency multiplier chain unit 54 of conventional type wherein that fixed frequency is successively quadrupled, then doubled, then tripled and finally again tripled until the frequency of the output voltage on coaxial line 55 is 270 megacycles per second. Line 55 is connected to serve as the input for excitation of the field in resonator 35, the resonant frequency of resonator 35 being 270 megacycles per second. A coaxial output line is provided at 56 for extracting energy from resonator 35.

Source 52 is coupled by coaxial line 57 to a frequency quadrupler 58, and the 15 megacycle per second output of the latter appears across the primary 59 of a coupling transformer. The transformer secondary 60 and a variable condenser 61 provide a tuned input circuit by which the 15 megacycle voltage is impressed between grid 62 and cathode 63 of a triode 64.

A condenser 65 and parallel inductance 66, forming a tuned circuit having a resonant frequency twice that of circuit 60, 61, are connected in the plate circuit of triode 64 in series with a variable potentiometer 67 which is suitably disposed across a convenient battery or like source 68 of plate current for triode 64, as illustrated. The alternating current circuit of triode 64 is completed to ground through by-pass condenser 69.

Triode 64 is operated to function as a frequency doubler whereby the alternating signal appearing on line 71 has a frequency double that of the input to grid 62. This 30 megacycle per second output of triode 64 is impressed between cathode 38 and grid 47 which is connected to ground through the conductive walls of cavity resonator 34. The unidirectional accelerating voltage for producing an electron beam from cathode 38 for projection through grids 41, 48, 49 and 51 is provided by a suitable source indicated at 72. This accelerating voltage is modulated by the alternating voltage on line 71. A blocking condenser 73 keeps this direct voltage out of the modulator circuit 74.

The above described arrangements for obtaining the recited frequency relations represent only a preferred manner of accomplishing the same, it being apparent that any equivalent manner of obtaining harmonically related input resonator and electron beam modulation frequencies lies within the scope of the invention, as will be determined in the claims. A decided advantage of the above described arrangement, however, is that both multiplier units 54 and 58 function as buffer stages for preventing disturbances in cavity res-

onator device 34 from affecting the source frequency. Also use of the same source frequency for both the modulating and input frequencies simplifies control problems.

In normal operation, the electron beam from cathode 38 is subjected to velocity modulation and electron grouping similarly to the amplifier of Fig. 1, and resonator 36 may extract energy from the velocity grouped beam at an output frequency which is a harmonic of the frequency of the input (270 mc.) frequency of resonator 36. Such frequency multiplier operation in general is known and described in Hansen et al. Patent No. 2,281,935 to which reference is made for further detail. In the illustrated device 34, by suitable adjustment of the tuning mechanism, the resonant frequency of resonator 36 may be adjusted to correspond to any of several harmonics of the input frequency of resonator 35. For example, in the selected type of frequency multiplier which was employed in a successful reduction to practice of the invention, resonator 36 is capable of being adjusted to be resonant at four different frequencies, corresponding respectively to the ninth, tenth, eleventh and twelfth harmonics of the input frequency to resonator 35.

Thus normally four separate frequencies are separately available from device 34 during its normal tuning range. These four frequencies are indicated by solid lines F_9 , F_{10} , F_{11} and F_{12} in Fig. 5, and will be referred to as the carrier frequencies available in the output of device 34, since they correspond to normal frequency F of the device of Fig. 1.

Through my invention, the number of frequencies available for extraction from resonator 36 is greatly increased without mechanical or physical changes in the cavity resonator device 34.

Variation of the electron beam acceleration voltage, as by the 30 megacycle per second modulating signal introduced on line 71, correspondingly varies the transit times of the electrons in the beam. This correspondingly varies the phase of the resulting electron concentrations relative to the input resonator field, and thus produces phase modulation of the electron grouping in the beam, similarly to the operation described above for Fig. 1. In this manner the electron beam grouping is phase modulated at a relatively low frequency which is rationally related to the bunching or velocity modulating frequency. By rationally related, it is meant that the ratio of the carrier or velocity-modulating frequency to the modulating signal frequency is an integer or a quotient of integers. The bunched electron beam is therefore phase modulated approximately in proportion to the alternating modulating voltage impressed on cathode 38.

These modulation effects produce an available output from the phase modulated grouped beam which consists of a number of carrier frequencies (harmonics of the input frequency to resonator 35), each having an infinite number of sum and difference sideband frequencies spaced at intervals corresponding to the frequency of the modulation voltage on line 71. Suitable tuning of resonator 36 makes available on line 56 any of these frequencies. It is desirable and preferable to have the modulation frequency a sub-harmonic of the exciting frequency of resonator 35. This will insure that the sidebands of one harmonic of the buncher frequency coincide with and reinforce the amplitudes of the sidebands of other harmonic frequencies, and thereby will

prevent occurrence of scattered sidebands of low amplitude at undesired frequencies within the tuning range. An integral number of sidebands is thus produced between each pair of adjacent harmonics within the tuning range of resonator 36. I have found that the choice of an odd sub-harmonic of the input frequency for the modulation frequency is preferable since it decreases the interval between sidebands when the number of sidebands is limited by the possible output at those sidebands.

While device 10 may be an amplifier and function according to the invention as explained in Fig. 1, it is preferably a frequency multiplier because the latter has better frequency stability for most purposes, and will produce more available frequencies. Moreover, the required modulation voltage is usually lower for a frequency multiplier than for an amplifier.

In the illustrated embodiment of Fig. 4, the described modulation frequency of 30 megacycles per second was chosen only because it was sufficiently high so that the carrier and sideband frequencies were readily separable and obtainable by tuning over the range of resonator 36.

In Fig. 5 the solid lines F_9 , F_{10} , F_{11} and F_{12} indicate the harmonic or carrier frequencies available from resonator 36. These are the harmonics that correspond to frequencies 2430, 2700, 2970 and 3240 megacycles per second and occur with no modulation voltage. The various sidebands are spaced apart by 30 megacycles, and are indicated by the dotted lines in Fig. 5. As further illustrated in Fig. 5, the sidebands thus produced are of substantial and almost equivalent amplitude.

The resonator device of Fig. 4 is prepared for operation by suitable energization and preliminary adjustments to obtain the proper exciting and modulation frequencies, the desired acceleration voltage on the cathode, and tuning of resonator 36 to one of its resonant frequencies. Only two adjustments are necessary after these preliminary adjustments have been made. First resonator 36 is tuned until the desired output frequency, carrier or sideband, is obtained in line 56. Then the plate voltage of modulator tube 64 is varied by potentiometer 67 until the lowest modulation voltage giving maximum amplitude in the output of resonator 36 is obtained. The potentiometer can be calibrated so as to indicate these optimum modulation voltages for each output frequency, and the tuning mechanism can be calibrated in terms of sidebands and carrier frequencies.

If desired, the amplifier of Fig. 1 may derive its input resonator and modulation frequencies from a common source, as in Fig. 4, or the input resonator and modulation frequencies in Fig. 4 may be derived from independently energized sources. The arrangement of Fig. 4, however, has frequency stability equivalent to that of the crystal controlled source, for each output frequency.

The sidebands should be at least 3 megacycles apart for normal cavity resonators, but where very high Q resonators are employed sidebands only 100 kilocycles apart may be separately obtained.

In use as a frequency standard, the apparatus of the invention may be used for calibrating wavemeters. It may also be used as a standard directly in the following manner. First, measure the unknown frequency f_x approximately by a wavemeter, and adjust the appara-

tus of the invention to produce the closest standard frequency f_c . Then introduce both f_c and f_x into a crystal rectifier mixer of known type, so as to produce a difference frequency output $f_c - f_x$ (or $f_x - f_c$). This difference frequency, which, for example, with the apparatus of Fig. 4 will always be less than 30 megacycles per second, can then be measured by any convenient known manner of accurately measuring frequency in this range.

Besides serving as a frequency standard for calibration and measurement purposes the apparatus of the invention may be used as a signal generator, as a source of power to replace a local oscillator with a stable frequency, and like applications. Also, where higher standard frequencies are desired, the output may be coupled to a suitable ultra high frequency multiplier. Other possible combinations are available for obtaining almost any desired standard frequency.

Instead of providing a modulation voltage on the cathode or some other beam control electrode, the same results can be obtained by phase modulating the output of sources 31 or 52 in such manner that both velocity and phase modulation of the electron beam is accomplished by its interaction with the field within resonator 35. This would enable the modulator unit 74 to be eliminated.

Furthermore, the invention provides a good frequency source for use in either or both the transmitter and receiver in a multi-channel microwave communication system. This would enable very narrow band operation in the system with a minimum of frequency control apparatus. The transmitter, for example, could comprise a frequency multiplier connected to a crystal controlled source as in Fig. 4, so as to provide a selective source of many transmitter frequencies, and the receiver could be similarly arranged and controlled.

Since many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

What is claimed is:

1. Ultra high frequency apparatus comprising means for providing an electron beam having electron grouping therealong at a rate of repetition corresponding to a carrier frequency, means for producing phase modulation of said electron grouping at a predetermined modulation frequency, and means for extracting energy from said beam only at a frequency differing from a multiple of said carrier frequency by an integral multiple of said modulation frequency.
2. Ultra high frequency apparatus comprising means for providing an electron beam having electron grouping therealong corresponding to a carrier frequency, and means for producing phase modulation of said grouping at a modulation frequency which is rationally related to said carrier frequency.
3. The apparatus defined in claim 2, wherein said modulation frequency is substantially a sub-harmonic of said carrier frequency.
4. A method of producing high frequency energy which comprises the steps of producing electron grouping in an electron beam at a rate of repetition corresponding to a carrier frequency, phase modulating said electron grouping,

at a frequency which is rationally related to said grouping frequency, and extracting alternating energy from said modulated beam.

5. A method of producing high frequency energy which comprises the steps of producing electron grouping in an electron beam at a rate of repetition corresponding to a carrier frequency, phase modulating said electron grouping at a frequency which is a sub-harmonic of said grouping frequency, and extracting alternating energy from said modulated beam.

6. Ultra high frequency apparatus comprising means for providing a resonant circuit oscillating at a predetermined frequency, means for projecting a beam of electrons in energy exchanging relation with said circuit for producing electron grouping along said beam, means for producing phase modulation of said electron grouping at a frequency which is rationally related to the frequency of said circuit, and means for extracting energy from said modulated beam.

7. The apparatus defined in claim 6, wherein said modulation frequency is a sub-harmonic of the oscillating frequency of said circuit.

8. The apparatus defined in claim 6, wherein said modulation frequency is an odd sub-harmonic of the oscillating frequency of said circuit.

9. Ultra high frequency apparatus comprising means defining a resonator adapted to provide an oscillatory electromagnetic field, means for projecting an electron beam through said field to produce electron grouping along said beam, modulating means for varying the flight time of said electrons at a modulation frequency which is a sub-harmonic of the frequency of said field, and means for extracting energy from said modulated beam.

10. The apparatus defined in claim 9, wherein said modulation frequency is an odd sub-harmonic of the frequency of said field.

11. A method of producing high frequency energy which comprises the steps of projecting an electron beam through an oscillatory electromagnetic field in such relation therewith as to produce electron grouping along the beam, varying the beam acceleration voltage for varying the flight time of said electrons at a modulation frequency rationally related to the frequency of said field, and extracting alternating energy from said beam by interaction of the beam with a tuned resonant circuit.

12. The method defined in claim 11, including the step of varying the average beam acceleration voltage for obtaining optimum output at the frequency of said alternating energy.

13. A method of producing high frequency energy which comprises the steps of modulating an electron beam to produce electron grouping therealong at a carrier frequency, phase modulating said grouping at a modulation frequency, and controlling both said carrier and modulation frequencies from a common source.

14. An ultra high frequency system comprising a frequency multiplier device of the cavity resonator type, cathode means adjacent thereto for projecting an electron beam through said device, a source of fixed relatively low frequency, a frequency multiplier unit connected to said source and to said device for delivering input field energy to said device at a frequency which is a relatively large multiple of said source frequency, and a second frequency multiplier unit connected to said source and to said cathode means for modulating the driving voltage of said

electron beam at a frequency which is a lower multiple of said source frequency.

15. The system defined in claim 14, wherein said second frequency multiplier unit comprises an electron discharge device having a plate electrode, and means for varying the plate current through said electron discharge device for determining maximum amplitude of output for said frequency multiplier device at its operating frequency.

16. In a method of selectively obtaining one of an integral sequence of stable frequencies, the steps of producing electron grouping in an electron beam at a rate of repetition corresponding to a carrier frequency, phase modulating said grouping at a modulation frequency, coupling said modulated beam to a resonant circuit, and tuning said circuit to resonance at a frequency which differs from a harmonic of said carrier frequency by an integral multiple of said modulation frequency.

17. The method defined in claim 16, wherein said modulation frequency is a sub-harmonic of the carrier frequency.

18. A method of producing high frequency energy which comprises the steps of velocity modulating an electron beam to effect velocity grouping of the electrons therealong at a carrier frequency, phase modulating said grouping at a modulation frequency, and extracting alternating energy from said beam at a frequency which differs from a harmonic of said carrier frequency by an integral multiple of said modulation frequency.

19. A method of producing high frequency energy which comprises the steps of producing a carrier frequency wave phase-modulated by a modulation frequency which is a subharmonic of said carrier frequency, velocity modulating an electron stream in accordance with said modulated wave to effect velocity grouping of the electrons therealong, and extracting alternating energy from said stream at a frequency which differs from a harmonic of said carrier frequency by an integral multiple of said modulation frequency.

20. A method of producing high frequency energy which comprises the steps of producing a carrier frequency modulated by a modulation frequency which is a subharmonic thereof, grouping an electron stream in accordance with said modulated carrier frequency, and extracting alternating energy from said stream at a frequency which differs from a harmonic of said carrier frequency by an integral multiple of said modulation frequency.

21. A method of producing high frequency energy which comprises the steps of grouping an electron stream in accordance with a carrier frequency modulated by a modulation frequency, and extracting alternating energy from said stream at a frequency differing from a harmonic of said carrier frequency by an integral multiple of said modulation frequency.

22. Ultra high frequency apparatus comprising a frequency multiplier device having a fundamental frequency cavity resonator, a tunable harmonic frequency cavity resonator, and means for producing an electron stream coupled to said resonators; means for supplying carrier frequency energy to said fundamental frequency resonator; and means for modulating said stream in accordance with a modulation frequency, said harmonic frequency resonator being tuned to a frequency differing from a harmonic of said carrier frequency by an integral multiple, including unity,

of said modulation frequency, whereby energy of said tuned frequency may be extracted from said stream.

23. High frequency apparatus comprising a frequency multiplier device having a fundamental tuned circuit, an output tuned circuit tunable over a range of harmonics of said fundamental frequency, and means for producing an electron stream coupled to said circuits; means for supplying an input wave to said fundamental frequency tuned circuit including a carrier frequency modulated by a modulation frequency which is a sub-harmonic of said carrier frequency; and means for tuning said output circuit to a frequency differing from a harmonic of said fundamental frequency by an integral multiple of said modulation frequency, whereby energy of said tuned frequency may be obtained from said apparatus.

24. High frequency apparatus comprising an electron discharge device having an input circuit tuned to a predetermined fundamental frequency, a tuned output circuit tunable over a range of harmonics of said input circuit frequency, and means for producing an electron stream coupling said circuits; means for supplying a carrier frequency to said input circuit of substantially said fundamental frequency; means for modulating said stream at a modulation frequency; and means for tuning said output circuit to a frequency differing from a harmonic of said carrier frequency by an integral multiple of said modulation frequency, said modulation frequency being greater than the band width of said output circuit, whereby substantially only a single frequency will be extracted from said stream.

25. Ultra high frequency apparatus comprising an electron discharge device having a fundamental frequency cavity resonator and an output cavity resonator separated by a field-free drift space, and means for coupling said resonators by an electron stream; means supplying a carrier frequency wave of substantially said fundamental frequency to said fundamental frequency resonator to velocity modulate and to produce velocity grouping of said electron stream at said carrier frequency, means for modulating said grouped electron stream at a modulation frequency, said output resonator being substantially tuned to a frequency differing from a harmonic of said carrier frequency by an integral multiple of said modulation frequency, whereby energy of said tuned frequency may be extracted from said stream.

26. Apparatus as in claim 25, wherein said modulation frequency has a value greater than the band width of said output resonator.
